ACOUSTICAL CORRECTION TILE

James R. Radcliffe, Williamsville, N.Y., assignor to National Gypsum Company, Buffalo, N.Y., a corporation of Delaware

Filed July 27, 1964, Ser. No. 81,012

Term of patent 14 years

(Cl. D18—2)

Fig. 1

Fig. 2

Fig. 3

FIG. 1 is a front face view of an acoustical correction tile showing my new design;

FIG. 2 is an edge view of said acoustical correction tile; and

FIG. 3 is a sectional view taken along the line 3—3 of FIG. 1.

I claim:

The ornamental design for an acoustical correction tile, as shown.
